COMBINED DESK AND SHELF UNIT THEREFOR FOR PHARMACISTS

Richard Kraft, 1030 Ranchero Way, Apt. 3,
San Jose, Calif.

Filed Apr. 12, 1965, Ser. No. 84,751

Term of patent 14 years

(Cl. D16—1)

Fig. 2.

Fig. 1.

Fig. 3.

Fig. 4

Fig. 5.

Fig. 6.

Fig. 7.

FIG. 1 is a front perspective view of a combined desk and shelf unit therefor for pharmacists showing my new design.

FIG. 2 is a rear perspective view of FIG. 1.

FIG. 3 is a front elevation of the pharmacist's appliance of FIGS. 1 and 2.

FIG. 4 is a side elevation of the same as seen from the left in FIG. 3.

FIG. 5 is a side elevation of the same as seen from the right in FIG. 3.

FIG. 6 is a rear elevation of the same as seen from the left of FIG. 4; and

FIG. 7 is a plan view of the same as seen from above in FIG. 3.

I claim:

The ornamental design for a combined desk and shelf unit therefor for pharmacists, as shown.
